UNITED STATES PATENT OFFICE.

BERT O. TILDEN, OF TRENTON, NEW JERSEY, ASSIGNOR TO AMERICAN SANITARY WORKS, OF TRENTON, NEW JERSEY, A CORPORATION OF NEW JERSEY.

WATER-CLOSET SEAT AND COVER HINGE.

1,251,448.

Specification of Letters Patent.

Patented Dec. 25, 1917.

Application filed September 17, 1917. Serial No. 191,675.

To all whom it may concern:

Be it known that I, BERT O. TILDEN, a citizen of the United States, residing at Trenton, in the county of Mercer and State 5 of New Jersey, have invented certain new and useful Improvements in Water-Closet Seat and Cover Hinges, of which the following is a specification.

This invention relates to improvements in 10 water-closet seat and cover hinges, and has for its object to provide a novel, simple and durable hinge mechanism of the class, for pivotally supporting both the closet seat and cover, and wherein, owing to the peculiar de- 15 sign and construction of the parts of the hinge, quite a wide range for "roughing in" measurements is allowed. A further object is to provide a combined hinge mechanism of the class, which is so constructed and ap- 20 plied that when the seat and cover are lifted or swung upwardly away from the bowl, they will stand erect or vertical of their own weight, and wherein the weight of the cover is utilized for balancing the seat, for 25 preventing either of said parts from accidentally gravitating toward the bowl. And a further object is generally to improve and simplify the construction and operation of 30 closet seat and cover hinges.

The various features and parts of the in- 35 vention will be understood from the detailed description which follows, and by reference to the accompanying drawing, in which—

Figure 1 is a top plan view of water-closet 40 outfit, having my improved hinge mechanism applied thereto.

Fig. 2 is a side elevation of the same; show- 45 ing by full and dotted lines the closed and open positions of the seat and cover.

Fig. 3 is an enlarged broken side view; 50 showing the cover and seat in vertical position, and the seat counterbalanced by the cover.

Fig. 4 is an enlarged top-plan view of the 55 hinge mechanism.

Fig. 5 is a vertical cross-section, taken on 60 line 5—5 of Fig. 6.

Fig. 6 is a central longitudinal section 65 taken on line 6—6 of Fig. 4; showing a straight post associated with the hinge mechanism.

Fig. 7 is a rear elevation of the seat, cover 70 and hinge.

In the drawing, 2 represents the closet

bowl, 3 the usual low-down flush tank, and 4 55 the flush pipe which connects said parts.

5 represents a seat of common form, and 6 represents a cover for the same. The hinge mechanism for the seat comprises a metallic leaf 7, which is preferably secured 60 to the underside of the seat by screws 8, the said leaf having two similar rearwardly projecting arms 9, said arms terminating in spaced upright cylindrical lugs or portions 10, which support a horizontal transversely 65 arranged rod 11, the latter passing through the lugs 10 and rigid and movable with said lugs. 12 represents similar hinge-posts, which are supported in spaced relation by the rearwardly projecting portion 2' of the 70 bowl, said posts having ball-like tops 13 which are perforated to pivotally receive the rod 11. The posts 12 have flanges 14, which rest upon the bowl, and below said flanges extend threaded stems 15, which pass 75 through suitable perforations in the ledge 2' of the bowl. The posts 12 are held rigidly in place by nuts 16, which engage the underside of the ledge 2'.

The cover 6 is provided with a hinge 80 mechanism comprising separate leaves 17, which are fastened to the underside of the cover by screws 17', and said leaves have rearwardly projecting arms 18, the latter provided with trunnions 19, which pivot in 85 sockets 19' located near the free ends of the upright lugs 10 (see Fig. 5). By this construction, the cover may be raised from the horizontal to the vertical position independently of the seat by the trunnions 90 19 turning in the sockets 19'. And both the seat and cover may be elevated from the full to the dotted line positions shown in Fig. 2, or from the dotted to the full line position shown in Fig. 3, by the pintle 95 rod 11 turning in the heads 13 of the post 12. The hinge members comprising the arms and lugs 9—10 are substantially L-shaped or like bell-cranks, which are pivoted substantially on the center 11 near the 100 point of the angle of said members. As explained, the seat 5 is mounted on the arms 9 with its longitudinal axis A, in line with the axis of the pivot 11. The cover 6 is disposed normally parallel to the seat and its 105 hinge members 17—18 are disposed parallel to the arms 9 of the said hinge. This disposes the pivot for the cover near the free

ends of the arms 10. Therefore, when the seat and cover are raised to the vertical position shown in Figs. 2 and 3, the lugs 10 are tilted backwardly into substantially horizontal position, and the entire weight 5 of the cover is shifted rearwardly or toward the tank 3, a sufficient distance from the center of pintle 11 to positively overcome the weight of the seat, and the tendency 10 of both seat and cover to gravitate toward the bowl 2 is obviated. As a matter of fact, this counterbalancing is so marked that the seat and cover will not fall even though they lack several degrees of being 15 raised to the true vertical position (see dotted lines *x* in Fig. 2). These features are important in case the plumber makes a mistake in his "roughing in" measurements and is obliged to set the closet bowl closer to 20 the tank than planned. The off-set posts 12 tend to position the main center 11 a sufficient distance from the tank, even though an error in the roughing in has been made, to allow the seat and cover to be raised to 25 substantially true vertical position, as shown in Figs. 2 and 3, where said parts will remain until lowered by the user of the closet.

In Fig. 6, I have shown a straight post 12', which may be substituted for the off-set post 12 for a still closer "roughing in." Either of said posts may be used interchangeably without requiring any alterations in the rest of the hinge mechanism.

Having thus described my invention, what 35 I claim as new and desire to secure by Letters Patent, is—

1. A combined closet seat and cover hinge, comprising a leaf adapted for supporting a closet seat, said leaf having spaced L-shaped 40 arms, a pintle rod passing through said arms substantially on the line of the longitudinal axis of said seat, similar independent leaves supporting a cover, said leaves having arms provided with trunnions which 45 pivot in sockets in said L-shaped arms, the axis of said trunnions being parallel to said pintle rod, and a pair of posts having perforated heads to pivotally receive said pintle rod.

50 2. A combined closet seat and cover hinge, comprising a pair of L-shaped hinge members adapted to support a seat, a rod con-

necting said members, said rod disposed in the line of the longitudinal axis of said seat, the corresponding free ends of said members having sockets, a pair of hinge elements adapted to support a cover normally parallel to the seat, said hinge elements provided with alining trunnions which are journaled in said sockets, and means for pivotally securing said hinge members to a closet bowl.

3. A combined closet seat and cover hinge, including a pair of bell-crank hinge members, corresponding arms of said members supporting a seat, and corresponding arms of said members being rigidly connected by a pintle rod disposed near the angle of said members, the latter arms having sockets near the free ends thereof, and a pair of hinge elements adapted to support a cover, said hinge elements having trunnions facing in opposite directions and engaging said sockets.

4. The combination with a closet bowl 75 and a movable seat and cover, of a seat and cover hinge mechanism comprising a leaf having two L-shaped members, a rod passing through both of said members near the angle of and movable with said L's, the corresponding free arms of said members provided with sockets facing each other, a pair of hinge elements, one end of said elements secured to the cover, the opposite end of said elements having trunnions pivoting in 85 said sockets, and a pair of posts mounted on the closet bowl and pivotally supporting said rod.

5. The combination with a closet bowl and a movable seat and cover, of a hinge 90 mechanism for the seat comprising a leaf having two-shaped members, a rod for rigidly connecting said members together, said rod disposed near the angle of said members, a pair of hinge elements for supporting said cover, said elements having trunnions adapted to engage sockets near the free ends of said members for holding the cover in position to counterbalance said seat when the said parts are raised from the 95 horizontal to the vertical position.

In testimony whereof I affix my signature.

BERT O. TILDEN.
